UNITED STATES PATENT OFFICE.

RUFUS B. SMITH, OF AKRON, OHIO.

GAME APPARATUS.

1,166,271.

Specification of Letters Patent. Patented Dec. 28, 1915.

Application filed August 30, 1915. Serial No. 47,989.

To all whom it may concern:

Be it known that I, RUFUS B. SMITH, a citizen of the United States, residing at Akron, in the county of Summit and State 5 of Ohio, have invented certain new and useful Improvements in Game Apparatus, of which the following is a specification.

The invention relates to a game apparatus, and more particularly to the class of 10 puzzle game apparatuses.

The primary object of the invention is the provision of an apparatus, wherein there is employed a board having upon one face indications representative of spaces and on 15 this board are adapted to be placed movable elements, such for example as blocks, which bear predetermined characters or indicia, such as numerals, so that on moving the elements in certain of the spaces and in given 20 order the numerals thereon will total fifty, when counted in several different directions, yet on counting the numerals in numerical order they will total one hundred and seventy, thus giving considerable amusement to 25 the player or user of the apparatus.

Another object of the invention is the provision of an apparatus of this character, wherein the arranging of the movable elements is rendered difficult to the player of 30 the game, so as to have the numerals when counted in four different directions total more than when counting the numerals in numerical order, thus requiring skill on the part of the player, as well as affording mental exercise.

A further object of the invention is the provision of an apparatus of this character, which is simple in construction, neat and attractive to the player, and inexpensive in 40 manufacture.

With these and other objects in view the invention consists in the features of construction, combination and arrangement of parts as will be hereinafter fully described, 45 illustrated in the accompanying drawing, and pointed out in the claim hereunto appended.

In the accompanying drawing; Figure 1, is a plan view of the playing board of the 50 apparatus constructed in accordance with the invention. Fig. 2, is a plan view showing the group of movable blocks with the numerals thereon used in the playing of the game.

55 Similar reference characters indicate cor-

responding parts throughout the several views in the drawing.

Referring to the drawing in detail, A, designates a board, which constitutes the playing base, preferably made from wood 60 and is of squared shape, having marked or otherwise indicated thereon square spaces B, arranged in rows, while certain of the spaces are colored, as green, as at 6, or the spaces occupied by the movable blocks 7 as viewed in 65 Fig. 2, to distinguish them from the spaces 5, which are not colored, in the respective rows. Upon this board A, are placed a series or group of movable blocks 7, preferably in disk form, each having mark or 70 otherwise impressed upon one face thereof a numeral, the numerals on all the blocks ranging from "1" to "3", "5" to "16", "18" and "20", there being seventeen blocks, and on positioning these blocks in certain order 75 upon certain of the spaces in the respective rows, and by counting the numerals in four different directions they will total in each row the sum of "fifty", thus the four totals aggregating the sum of "two hundred", yet 80 when adding the numerals in numerical order on all of the blocks the total will be "one hundred and seventy." The arranging of the blocks 7, is rendered difficult, as the same have to be placed in a particular order upon 85 only the colored spaces 5, so that the total sum of "fifty" can be added in four different directions, for solving the puzzle.

From the foregoing it is thought that the construction and manner of arrangement of 90 the game for solving the same is clearly understood, and therefore a more extended explanation has been omitted.

What is claimed is:

The herein described game apparatus, including a board divided into a plurality of squares, certain of which are of a different color from the others, and a plurality of movable blocks corresponding to the number of squares of one of the colors and each 100 block carrying a number different from the others, by means of which a variety of arrangements of the numerals relatively to the squares is permitted and whereby the various numerals may be combined to produce like results when the numerals are 105 added in lines of different directions.

In testimony whereof I affix my signature.

RUFUS B. SMITH.
